[57] ABSTRACT

A machine capable of producing various shaped high density concrete products automatically when its associated mechanical components, including a pre-shaped mold box, insertable and retractable core plugs and tiltable double faced tamping device are caused to perform their specific functions in timed sequence.

AUTOMATIC CONCRETE FORMING MACHINE FOR PRODUCING HIGH DENSITY PRODUCTS

BACKGROUND OF THE INVENTION

This invention relates to machines for producing high density concrete products.

1. Field of the Invention

This invention is particularly directed to a concrete forming machine which utilizes a combination of hydraulic and pneumatic power to operate the functioning components of the machine in proper sequence to automatically produce high density concrete products having greater strength at a low cost.

2. Description of the Prior Art

Heretofore small items such as water meter boxes, building blocks, fence components and the like have not been successfully made out of high density concrete since the time and labor necessary was prohibitive. Thus, a need exists for these high density items, particularly since they last much longer in use than the same item made out of normal density concrete.

SUMMARY OF THE INVENTION

In accordance with the invention claimed, an improved concrete forming machine is provided which may be operated by one man to automatically and speedily produce high density concrete products having the necessary strength required for various structural uses, such as water meter boxes (shown), building blocks, fence components and the like.

It is, therefore, one object of this invention to provide a new and improved apparatus for forming automatically high density products.

Another object of this invention is to provide an improved machine for forming high density water meter boxes from concrete.

A further object of this invention is to provide an improved mold loading, pressing and core removing apparatus for sequentially forming a plurality of like concrete products by a single operator.

A still further object of this invention is to provide high density concrete products from a dry mix automatically and sequentially at a low cost.

Further objects and advantages of the invention will become apparent as the following description proceeds and the features of novelty which characterize this invention will be pointed out with particularity in the claims annexed to and forming a part of this specification.

BRIEF DESCRIPTION OF THE DRAWINGS

The present invention may be more readily described by reference to the accompanying drawing in which:

FIG. 1 is a front elevation of the concrete forming machine of this invention with its functioning components shown in at rest position.

FIG. 2 is a left side elevation of the machine shown in FIG. 1.

FIG. 3 is a fragmentary right side elevation partly in section on the line 3—3 of FIG. 1 illustrating the elevator mechanism of the invention.

FIG. 4 is a fragmentary sectional plan view taken substantially on line 4—4 of FIGS. 1 and 2 illustrating the relation of the core plugs to the mold box of the invention.

FIG. 5 is a fragmentary vertical sectional view taken substantially on line 5—5 of FIG. 1 illustrating the tiltable double faced tamping device of the invention.

FIG. 6 is a fragmentary vertical sectional view taken on the line 6—6 of FIG. 4, through the stationary mold box and work counter illustrating the initial respective positions of the retractable core plugs and elevator mechanism when these elements are static and the mold box is empty, ready to receive the raw concrete material to form the high density concrete meter box.

FIG. 7 is an enlarged fragmentary view similar to FIG. 6 illustrating the first step or sequence of operation of the machine required to fabricate the product, showing the core plugs inserted into the mold box and the cavity of the mold box loosely filled with a raw concrete mixture, and the main tamper foot in position for activation.

FIG. 8 is a view similar to FIG. 7, illustrating the next step or sequence of operation of the machine and showing the concrete mixture compacted by successive reciprocal movements of the main tamper foot to occupy approximately one half the vertical height of the mold box cavity.

FIG. 9 is a view similar to FIG. 7, illustrating the next step or sequence of operation and showing the upper half portion of the mold box cavity loosely filled with the raw concrete mixture to its extreme top with the dual tamping member having been tilted or rotated ninety degrees (90°) to bring the top or finishing tamper foot into position for activation.

FIG. 10 is a view similar to FIG. 9, illustrating the next step or sequence of operation and showing the upper one half portion of the loosely filled concrete mixture in the mold box cavity after compaction by successive reciprocal movements of the top or finishing tamper foot, thereby completing the necessary operations required for producing a high density concrete water meter box.

FIG. 11 is a view similar to FIG. 10 illustrating the final step or sequence of operation of the machine required to make ready for removal of the finished meter box from the machine by a lift truck or other suitable equipment, and shows the core plugs retracted from the mold box and the finished meter box raised to a position several inches above the work counter surface, still supported by a removable ring member on the upward projecting tines of the elevator mechanism.

FIG. 12 is a schematic diagram illustrating the hydraulic system employed for operating and controlling some elements of the machine.

FIG. 13 is a schematic diagram illustrating the pneumatic system employed for operating and controlling other elements of the machine.

FIG. 14 is a perspective view of the finished meter box still supported on the removable ring ready for air curing and storage.

DESCRIPTION OF THE PREFERRED EMBODIMENT

Referring now to the several views of the drawings for a more detailed description of the construction and other features of the invention by characters of reference, FIGS. 1 and 2 illustrate the complete assembled automatic concrete forming machine 10 of this invention, which comprises the rigid structural frame 11 having secured thereto between the vertically disposed "I" beam members 12 and 13 of the frame a rigid counter

top or work table structure 14. Work table structure 14 is adapted to support a preformed mold box 15 in integral relation therewith by means of transverse structural members 16.

A material supply delivery chute 17, having upwardly extending flanged sides 18, is directly connected to similar flanged sides 19 which are integral with and extend upwardly from the top surface 20 of the work table structure 14, in any suitable manner such as by welding, to provide a raw material delivery source to the top surface 20 of the work table from a material mixer (not shown).

The vertical I-beam members 12 and 13 of the frame structure 11 are rigidly connected at their upper ends by a transverse I-beam member 21 and at their bottom ends by a heavy support plate member 22 which is preferably embedded in a concrete slab 23 and securely anchored thereto by suitable anchor bolts 24. The entire rectangular structural frame 11 is further rigidly maintained in a plumb vertical position by means of the horizontal tie bars 25 and/or other structural support members (not shown).

Surrounding the lower ends of the vertical I-beam members 12 and 13 and extending transversely therebetween, while providing suitable clearance from said members, is an elevator mechanism 26 which is adapted to rest in its lowermost position slightly above the surface of plate member 22 on stops, such as the heads of anchor bolts 24. The purpose and function of the elevator mechanism 26 will be further explained as this description proceeds.

Mounted between and adjacent the flat inner surfaces of the vertical I-beam members 12 and 13 in the upper portion of the frame 11 is a U-shaped reciprocating frame member 27, to the lower flange 28 of which is attached by welding or otherwise a pair of depending angle members 29. Angle members 29 are adapted to support in rotative relation the tiltable double-faced tamping device 30. The U-shaped frame 27 and attached tamping device 30 are supported and reciprocated down and up as a single unit by means of the rigid attachment 31 of the frame to the lower extending end of piston rod 32 which protrudes from the bottom end of its operating pneumatic cylinder D.

It is imperative that the moving and stationary components of the concrete forming machine 10 so far described must be maintained in near perfect vertical and horizontal aligned relationship during the operation of the machine. Misalignment of any of said components would cause improper contact and possible rupture of the machine parts and destruction of the product being fabricated. To prevent such an occurrence, the moving components of the machine such as elevator 26 and U-frame 27 with its supported tamping device 30 are maintained in vertical and horizontal alignment with stationary work table 14 and its associated mold box 15 by means of a plurality of eccentrically adjustable rollers 33. Rollers 33 are suitably spaced and mounted on the moving components and adapted to provide rolling contact with the flat inner or outer faces and the forward or rearward projecting edge surfaces of the legs of the vertical I-beams 12 and 13, as shown in FIGS. 1 and 2.

The preformed mold box 15, utilized to fabricate or automatically produce the desired finished product, for example, a high density concrete water meter box or housing 34 shown in FIG. 14, rests on its individual, re-

movable retaining ring 35. Housing 34 and ring 35 are removed from machine 10 after a molding operation so that housing 34 may be set aside for air curing. The housing 34 is substantially a hollow cube in form having narrow perpendicular side walls 36 with rounded outside corners defining a rectangularly cross-sectional configuration. The housing is additionally provided with a flat bottom surface 37 and a top end surface 38 defining a rectangular opening 39 exposing a hollow interior 40 which extends from top to bottom of the cube. The perpendicular walls 36 are thickened at their top inside surfaces to provide a suitable ledge 41 which extends around the inside perimeter of the walls to support the usual metal meter box cover (not shown). The ends of box 34 are also provided with suitable arched openings 42 which extend to and through the bottom surfaces 37 of the box to allow for the passage of various size pipes (not shown) during installation of the meter box.

The mold box 15 is preformed to fabricate the water meter box described in the preceding paragraph or any other desired product and comprises exterior, continuous wall 43 forming the perimeter of the box which, together with the centrally located interior core member 44 having a flat closed top 45 and a closed bottom 46, forms the continuous rectangular mold cavity 47. The width of the cavity is substantially the same as the desired wall thickness of the finished meter box 34. The exterior opposite ends of walls 43 and the adjacent opposite end walls of the interior core member 44 are each provided with arcuate topped cutouts or openings 48 and 49, respectively, which are adapted to receive in sliding relation suitably shaped, insertable and retractable core plugs 50 and 51, respectively. These core plugs are adapted to form the arched openings 42 in the finished meter box 34.

The preformed mold box 15 is centrally located and preferably installed midway between the inside surfaces of the vertical I-beams 12 and 13, and the flange sides 19 of the work table structure 14, which in turn are rigidly connected by means of bolts or otherwise to the inside surfaces of the I-beams. The mold box 15 is also rigidly supported by and secured at its bottom end to the transverse structural members 16 which form an integral part of the work table structure 14. The continuous perpendicular side walls 52 of the interior core member 44 being accurately spaced an equal distance inwardly from the inside face of the exterior walls 43 to form the mold cavity 47 is open at both its upper and lower ends 53 and 54 to allow for raising and removal to secure and support the unattached interior core member 44 in its spaced relation from the exterior walls 43 by suitable cross ties 55. These cross ties are preferably welded to the closed bottom 46 of the core member and to the transverse structural member 16 as shown in FIGS. 1, 4, and 6 through 11.

The top surface 20 of the work table 14 is provided with an opening 56 which mates with exterior perimeter wall 43 of the mold box 15, into which it extends and is secured by welding to form the outer perimeter of the mold cavity 47. The mold cavity 47 extends to the top surface 20 of the work table 14 and together with the flat closed top 45 of the interior core member 44 forms a wide open end 53 of the cavity, which forms a material receiving access opening 53' in the top surface 20 of the work table 14.

The elevator mechanism 26 which is used to support the concrete water meter box 34 in the process of fabrication and to lift the finished box up and out of the mold cavity 47 is best illustrated in FIGS. 1, 2 and 3. This elevator mechanism 26 comprises a pair of front and rear transverse structural I-beams 57 and 58, respectively, which extend across the front and rear of the vertical I-beams 12 and 13, and at their outer ends are joined, as by welding, to upwardly extending side plate members 59 and 60, and to the pairs of front and rear angular reinforcing plate members 61. These described structural components are adapted to form an open-topped box-like structure, which surrounds but which has clearance from the vertical I-beam members 12 and 13. The box-like structure may be easily raised and lowered in exact alignment with the other machine components, such as the mold box 15, by means of the eccentrically adjustable rollers 33, which contact and roll on the outside faces and front and rear edge surfaces of the vertical I-beam members 12 and 13.

Integral with or removably secured to the top surfaces of the I-beams 57 and 58 is a flat plate member 62 to which are attached a plurality of flat-topped rods or tines 62' which project perpendicularly to, and are located on the plate member 62 to extend slightly into the center of the mold cavity 47. At this point their flat tops are utilized to support one of the individual retaining rings 35, upon the top surface of which the water meter box 34 is being formed.

The structural portion of the elevator mechanism 26 may be raised or lowered as desired by the controlled simultaneous action of the hydraulically operated cylinders B and C, shown in FIG. 12, which are each universally mounted at 63 between the rearwardly extending legs of the vertical I-beams 12 and 13 shown in FIGS. 1 and 3. As the lifting apparatus associated with hydraulic cylinders B and C are identical, it will suffice to describe only one of them, which is shown in detail in FIG. 3 on the right side of the machine.

The lower ends of piston rods 64 of cylinders B and C are connected at 65 to the upper ends of a bifurcated bar or fork member 66 which are adapted to straddle a plate 67. Plate 67 is integrally attached to the top face of the rear transverse I-beam 58 and projects inwardly therefrom, between the sides of the fork members 66. Directly below plate 67, mounted in the sides of fork member 66, is a transverse pin or bolt 68. A stop plate 69 is secured in horizontal position by welding to the rear side of the vertical I-beam web 70 and limits the downward movement of the fork member 66. Near the top of fork members 66, between their inner sides, and journaled on a shaft 71, is a freely rotatable idler sprocket 72, over which a suitable link chain 63 is adapted to ride. Chain 63 is secured at its forward bottom end 74 to I-beam web 70 and at its rearward bottom end 75 to plate 70.

It should be noted that chain 73 is somewhat longer than necessary, thereby resulting in a bulged or slack portion in the rear portion of the chain as at 76, when the elevator mechanism 26 is in its at-rest position as shown in FIGS. 1 and 3. This condition provides for a slow and gentle upward initial movement of the elevator mechanism with its associated lifting tines 62' contacting the retaining ring 35 to cause the initial breaking away of the walls of the completed water meter box 34 from the walls of the mold cavity 47 without damage to the finished product. This slow and gentle initial lift-

ing movement becomes faster as chain 73 overrides the idler sprocket 72 and becomes taut, thereby quickly lifting the finished meter box from its forming mold as shown in FIG. 11.

Referring now to FIGS. 1, 4, 6, 11 and 12 of the drawings, these figures show the core plugs 50 and 51 in their retracted or inserted positions to perform their particular function of forming the arched openings 42 in the end walls of the concrete meter box 34. A hydraulic mechanism in association with these core plugs is utilized to perform the intricate function of inserting and retracting these plugs. The core plugs 50 and 51 are formed to the desired arched top, straight sided and open bottomed shape of openings 42 and are provided with a central bore 77 which extends through the plugs. The reduced outer end portions 78 of plugs 50 and 51 have flat top and bottom surfaces to which are attached the bifurcated, rigid lever arms 79 which extend rearward and parallel to the side flange portions 19 of the fixed work table structure 14. At this point 80 the lever arms are integrally connected to the inwardly projecting, right angle extension portions 81 and 82, respectively, of the lever arms 79. Top and bottom portions of extensions 81 and 82 are joined to the bifurcated lever arms 79 at 80 and at their inner opposed ends 83 by connecting blocks which form lever arms 79, and their right angle extensions 81 and 82. This connection forms a pair of L-shaped units. When these L-shaped units are activated by means of the hydraulically operated cylinder A, they will cause core plugs 50 and 51 to be moved inwardly or outwardly substantially at the same time so as to either insert or retract the core plugs into or from openings 48 and 49 of the mold box 15.

To accomplish this result, the opposed extensions 81 and 82 of lever arms 79 are provided with suitable bores therethrough for receiving a transverse shaft 84. Shaft 84 is fixed at its opposite ends to flanged sides 19 of the work table 14 to firmly support in sliding relation thereon the opposed lever arm assemblies. The fixed transverse shaft 84 is also provided with adjustable stop collars 85 which limit the inward movement of these lever arms.

The core plugs 50 and 51 are slidably mounted in their bores 77 on inwardly projecting studs 86 which are fixed in exact horizontal and vertical alignment with the centers of the mold box cutouts 48 and 49 to the rear legs of the vertical I-beams 12 and 13. This arrangement firmly supports the core plugs as they are moved in and out during fabrication of the meter box. It should be noted that the core plugs 50 and 51 are provided with smooth flat bottomed surfaces 87 which are adapted to slide easily and directly on the smooth, flat top surface 88 of the individual retaining rings 35 as shown in FIGS. 6 through 10, inclusive, when said rings have been inserted in the mold cavity 47, resting on the flat top ends of the support rods 62'.

The hydraulic operated cylinder A is mounted directly forward of and in parallel alignment with the transverse shaft 84 and is pivotally secured on one end at 89 to one of the lever arms 79. Its piston rod 90 is pivotally secured at 91 to the other and opposite lever arm 79. Cylinder A is provided at each end with suitable hydraulic lines or hoses 92 and 93 which supply the necessary oil pressure to move the piston shaft and/or the cylinder itself in the desired direction, to retract or insert the core plugs 50 and 51 from the openings 58

and 59 in the walls of the mold box 15, as desired, to complete the fabrication of the meter box 34.

FIGS. 1, 2 and 5 of the drawings illustrate the various features of the novel tiltable, double-faced or footed tamping device 30 used in conjunction with the other components of the complete assembled machine 10 to fabricate the concrete meter box 34. In these figures device 30 is shown in its normal, at-rest position, relative to the other machine components, or ready to begin the initial fabricating operation of the product.

The tiltable, double-footed tamping device 30 comprises a suitably shaped body structure 92' to which is integrally attached the forward facing finishing foot 93' and the downward facing main foot 94 which are positioned at right angles to each other, as shown in FIG. 5. The main tamping foot 94 is a continuous flat bottom surfaced ring which is similarly shaped to retaining rings 35; but is much narrower in cross section, as shown in FIG. 8, to allow for escape of air from the mold box cavity 34 during its tamping function. The finishing foot 93' has a slightly curved tamping surface 95 forming a part of the integral formed ring flange 96, which together with the curved tamping surface 95 are adapted to finish the curved top end surface 38 and the continuous ledge 41 of meter box 34, as shown in FIG. 1 and 11 of the drawings.

The tamping device 30 is provided with an integral sleeve 97 which extends transversely between the side walls of the body structure 92 and is provided with a central bore and bearing surface through which the transverse axle shaft 98 extends. Shaft 98 is supported at both ends by the depending angle members 29 in tiltable or rotative relation to the reciprocal U-frame member 27, as previously described.

Tamping device 30 may be tilted to bring the finishing foot 93' (as shown in full lines in FIG. 5) into position for the finish tamping operation (as shown in dotted line in FIG. 5) by the activation of the pneumatically operated air cylinder E. Cylinder E is pivotally mounted at its top end to the arm of bracket 99 which is secured to the front face of U-frame web 100, clearly shown in FIG. 1. Cylinder E's piston rod 101 extends downward through a slot 102 in the lower flange 28 of the U-frame, where its lower end is pivotally attached at 103 to the adjacent upper side wall of the tamping device body structure 92'.

Cylinder E may be activated through the control valve (A-2) which is mounted on the front of the U-frame member 27 and receives its supply of air under pressure through flexible hose or line 104 from a source of pressurized air supply such as the compressor 105 which is driven by a motor 106 (see FIG. 13).

Control valve A-2 is connected to the top of cylinder E by an air supply line 107 to the bottom of cylinder E by an air supply line 108. When valve A-2 is positioned, as shown in FIG. 13, air under pressure will be delivered to the top of piston 109, causing the piston and its attached piston rod 101 to be forced downwardly, thereby applying force to the pivotal attachment 103 at the point where the end of the piston rod is connected to the body structure 92 of the tamping device 30. This causes the pivotal point of attachment to move radially in an arc about the axis of the transverse axle shaft 98, causing the entire tamping device to be tilted or rotated exactly 90°, bringing the finishing foot 93' into tamping position for use as shown in dotted line in FIG. 5.

When it is desired to tilt the tamping device 30 back to its original position, shown in full lines in FIG. 5, with the main tamping foot 94 in position for use, this reverse tilting movement may be readily accomplished by adjusting the valve A-2 to allow pressurized air to move through line 108 to the bottom of cylinder E, thereby forcing piston 109 upwardly and retracting the piston rod into the cylinder. This action causes the tamping device 30 to be returned to its original position. The air on the downstream side of the piston is exhausted during either cycle of movement through suitable exhaust ports, such as exhaust port 110 in valve A-2. Set screws 111 are provided in the lower flange 28 of the U-frame member 27 which contact the top edges of the body structure 92' of the tamping device. These set screws may be adjusted to maintain the tilting radial movement of the device to 90°, more or less, as desired for accurate alignment of the tamping device.

The tamping device 30 and the U-frame member 27 to which it is attached are designed to be reciprocated as a single unit, down and up in a vertical direction between the vertical I-beams 12 and 13. The adjustable rollers 33 maintain accurate vertical and horizontal alignment of the tamping device 30, and especially its tamping feet 93' and 94, with respect to the mold cavity 47 and the access opening 53' in the table top surface 20, as shown in FIGS. 7 through 11.

The downward force or thrust on the U-frame member 27 and its associated tamping device 30 required to perform the tamping function is provided by the combined weight of the unit and the operation of the large and powerful pneumatic cylinder D. The top of cylinder D is pivotally mounted at 112, midway between the vertical I-beam members 12 and 13 to the top transverse I-beam 21, from which it extends vertically downwardly. Its piston rod 32 extends downward from its bottom and is rigidly attached at 31 to the center of the transverse web 100 of the reciprocating U-frame member 27, as shown in FIG. 1.

The lower end of cylinder D is provided with a frame structure 113 which straddles the web 100 of the U-frame member and is provided on its lower surface with two pairs of flexible rubber bumpers 114. These bumpers are adapted to contact the upper surface of the U-frame member's lower transverse flange 28 to absorb the initial shock on cylinder D when the U-frame member is sequentially returned during the tamping operations to its upper position, thereby preventing damage to the cylinder D and its associated elements.

Cylinder D is provided at its upper end with a flexible air-line hose 115 which extends through an opening in the leg of vertical I-beam frame member 13 and downwardly to where it is connected to the main double acting control valve A-1. Control valve A-1 receives pressurized air through a line 116 from compressor 105. Cylinder D is provided at its lower end with a suitable fitting which supports a quick relief valve A-3 which is also connected through a flexible air line hose 117 to another port in the control valve A-1. The quick acting relief valve A-3 provides instant relief of any residual pressure in the lower portion of cylinder D to thus increase the downward velocity of the tamper foot.

OPERATION

Reference is now made to the sequence of operation of the machine as shown in FIGS. 7 through 11 of the drawing and to the schematic diagrams of the hydraulic

and pneumatic systems shown in FIGS. 12 and 13 illustrating the operation of the machine in fabricating a high density concrete water meter box shown in FIG. 14. It should be noted that the various components of the machine shown in FIGS. 1-6 are in their respective positions at the start of a fabrication or forming operation.

The first step in the operation of the machine is to insert core plugs 50 and 51 into openings 48 and 49 in the ends of mold box 15. This is accomplished by actuating or positioning the hydraulic control valve V-1, as shown in dotted lines, to allow oil under pressure from a suitable pump 118 to move through feed line 119, valve V-1 and its line 120', and line 92 into cylinder A, causing piston rod 90 to be retracted into cylinder A, pulling lever arm 79 toward one side of the mold box 15. This action causes core plug 51 to be inserted into the openings in one end of the mold box. Core plug 51 is stopped at the desired position by contact of end 83 of extension 82 with one of the adjusting collars 85, immediately after which the core plug 50 on the opposite side of the mold box is caused to be inserted in the openings 48 and 49 in the opposite end of the mold box. This action occurs by the continued oil pressure on the piston of cylinder A, which causes the cylinder itself to be moved laterally, together with the attached lever arm 79-81 until the end of lever arm 81 is stopped against the other stop collar 85, thereby resulting in the proper insertion and positioning of both core plugs 50 and 51 in the mold box 15 as required to continue the fabrication of the meter box.

After the core plugs 50 and 51 have been inserted in the mold box 15, as above described, a predetermined amount of premixed but raw concrete material is delivered down the chute 17 from the mixer (not shown) to the rear top surface 20 of the work table structure 14. Approximately one half of this material is scraped from the table top surface 20 into the mold box cavity 47 to completely fill said cavity to its upper open end 53 with this loose material resting on the flat top surface 88 of the individual retaining ring 35. Ring 35 has previously been placed in the mold cavity 74, where it rests on the top flat surfaces of the elevator rods or tines 62'. The material in the mold cavity 47 surrounds core plugs 50 and 51, as shown in FIG. 7.

The loose material in the mold cavity 47 is then tamped, as shown in FIG. 8, by the reciprocating action of the main tamping foot 94 of the tamping device 30 and by the combined weight of said device and the associated U-frame member 27. The downward thrust is created when air pressure is applied to the top of the piston in the pneumatic cylinder D when the control valve A-1 is repeatedly activated to provide this action. This action results in the loose material being compacted into a dense mass which occupies approximately one half of the height of the mold cavity 47.

The remainder of the material left on the table surface 20 is then placed into the mold cavity 47 directly on top of the previously compacted material which occupies the lower half of the cavity represented in FIG. 9 by the broken line 120. This remainder material fills the upper half of the mold cavity 37 with loose material which extends slightly above the upper open end of the access opening 53' in the table top. After this second filling of the remaining cavity space is accomplished, the tamping device 30 is tilted or rotated 90° to bring the finishing tamping foot 93' into alignment with the

top surface 20 of the work table structure 14 and the access opening 53' of the mold cavity 47. This tilting action is accomplished by the activation of the pneumatic valve A-2 as previously described. This upper half portion of loose material is then compacted into a dense mass by the reciprocating action of the tamping device 30 and the U-frame member 27 in the same manner as the lower portion of the material was compacted by the main tamping foot 94, described above.

10 The tamping action of the finishing foot 93' results not only in the compaction of the upper portion of loose material into a dense mass, but also joins the upper and lower portions of compacted material into a single homogeneous, perpendicular wall structure 36

15 which forms the meter box 34. In addition the tamping foot 93' provides for the formation of the continuous ledge 41 in the interior of the meter box, resulting in a slightly curved top end surface 38 to the finished meter box 34, as shown in FIGS. 11 and 14. It should also be understood that the degree of compaction of the loose concrete material is carefully controlled by the number of reciprocal tamping movements of the tamping feet to assure the desired finished height of the meter box 34.

20 25 Since the meter box 34 has been completely formed by the preceding operations, as shown in FIG. 10, it only remains necessary to carefully remove the finished meter box from the preformed mold box 15 without damage to the uncured box and to place the box on a suitable rack for air curing.

Reference should now be made to the sequence views of FIGS. 10 and 11 and the schematic diagrams shown in FIGS. 12 and 13 for explanation of the final operation of removing the finished meter box 34 from the machine. The pneumatic control valve A-1 should be adjusted to allow air under pressure to enter the cylinder D at its lower end. This occurs by air pressure passing from the compressor 105 through line 116, line 121 of the valve A-1, line 117, and automatic relief

30 35 valve A-1 to the bottom of cylinder D, thus causing the finishing tamper foot 93', the tamping device 30 and the reciprocating U-frame member 27 to be raised to its normal (at-rest) position as shown in FIG. 1. This apparatus is maintained in this position by the continued pressure of air on the underside of the piston in cylinder D. The spent air is evacuated to atmosphere from the top of the cylinder through the line 115 and exhaust port 112 (shown in dotted line) in valve A-1.

40 45 During the above operation all of the ports in the tilt valve A-2 may be adjusted so that a port 123 (shown in dotted line) in the valve is in communication with the air lines 104 and 108, thus causing piston 109 in cylinder E to be raised (as shown in FIG. 13), and the spent air above the piston to be evacuated to atmosphere through line 107, port 124 (shown in dotted line) in the valve A-2, and exhaust port 110. This operation results in the return of the tilttable tamping device 30 to its normal position as shown in FIGS. 1 and 13, i.e. with the main tamping foot 94 facing downward

50 55 ready to resume its tamping function on another meter box unit.

60 65 The next step or operation required is the removal of the core plugs 50 and 51 from their position in the mold cavity 47 of the mold box 15. This is accomplished by reversal of the procedure as previously described for the insertion of the core plugs into the cavity 47 of the mold box. Hydraulic control valve V-1 is adjusted to let

oil under pressure from the pump 118 move through line 119, valve V-1 and line 93 into the end of cylinder A where it exerts pressure on the piston (not shown). This action causes piston rod 90 to retract lever arms 79 and 82 and core plug 51 from the mold box cavity 47, as shown in FIGS. 11 and 12, to a position flush against the flanged side 19 of the work table 14 which stops the outward movement of the core plug 51. Continued hydraulic pressure on the piston in cylinder A which is stopped from further lateral movement causes cylinder A itself to be moved outwardly together with lever arms 79 and 81, thereby retracting core plug 50 from the mold box cavity 47, as shown in FIG. 11.

During the above described operation, hydraulic fluid or oil from the opposite side of the piston in cylinder A is returned to a reservoir 125 through line 92, valve V-1, line 126 and the interconnected return line 127. A suitable relief valve 128 is connected between the pressure line 119 and the return line 127 to prevent any sudden surges of pressure from being exerted on the valves V-1 and V-2 or other components in the hydraulic system to provide a smooth uninterrupted operation of these parts.

Having thus removed the tamping device 30 and the core plugs 50 and 51 from any possible interference with the final removal of the finished concrete meter box 34 and its retaining ring 35 from the mold box, the meter box and retaining ring are removed from the mold box as follows:

Hydraulic control valves V-1 and V-2 are adjusted to allow fluid under pressure to pass from source 106 through line 119, valve V-1, the upper portion of line 93, to and through valve V-2, to line 129, which is connected to the interconnecting line 130 which communicates with the lower ends of the hydraulically operated cylinders B and C as shown in FIG. 12. The pressure applied to the cylinders B and C simultaneously is adapted to raise the pistons in both cylinders, thus lifting the elevator mechanism 26 (as previously described) from its at-rest position shown in FIGS. 1 and 2, together with tines 62' which are in contact with the flat underside surface of the retaining ring 35, the retaining ring 35 and the meter box 34 resting on its upper surface 88. This raising action occurs very slowly for the first one half inch or so to gently break the perpendicular walls 36 of the meter box from the adjacent walls of the mold cavity 47, thereby protecting the walls of the newly formed meter box from damage which might otherwise be incurred by a sudden movement of the tines 62'.

After this slow initial upward movement of the elevator mechanism the remaining lift of the retaining ring 35 and the uncured concrete meter box 34 is quickly accomplished by the faster upward movement of the tines 62' to a position several inches above the top surface 20 of the work table 14. Enough space is provided between the top surface of the work table and the retaining ring to allow for the insertion of the fork or tines of a lift truck under the retaining ring 35 to lift and remove the meter box from the machine and place it on a suitable storage rack for air and water curing.

Having thus quickly fabricated and removed one finished high density concrete meter box from the machine, the machine is quickly arranged for sequential production of additional boxes by valve V-2 being positioned to allow the elevator mechanism to return by gravity to its original lower starting position (shown in

FIG. 1). The hydraulic fluid in cylinders B and C is caused to return to reservoir 125 through the interconnecting line 130, line 129, port 131 in the valve V-2 (shown in dotted line) and return line 125.

Although but one embodiment of the invention has been shown and described, it will be apparent to those skilled in the art that various changes and modifications may be made therein without departing from the spirit of the invention or from the scope of the appended claims.

I claim:

1. A molding apparatus comprising:
a mold box open at its top and bottom,
a vertically arranged core disposed within said mold box and spaced therefrom to form a space around the core between the mold box and the core,
a molding ring disposed within said space between said mold box and said core at the lower end of said mold box and arranged to close the lower end of said space,
said molding ring being slidably movable in said space,
a means for supporting said molding ring at the bottom of said space in said mold box,
said mold box defining an opening extending laterally of its top and bottom and extending into said space between said mold box and said core,
a core plug reciprocally mounted on said apparatus for movement into and out of said opening,
said core plug being inserted into said opening during a molding operation and being retracted from said opening prior to a mold box evacuating operation,
a tamping mechanism mounted on said apparatus for reciprocally moving into the opening at the top of said mold box and said space between said mold box and said core for compacting material previously placed in said space,
means for sequentially actuating said tamping mechanism to tightly compress the compressible material, and
means for slidably moving said mounting ring in said mold box from its bottom to its top for pushing the compacted material from said mold box,
said tamping mechanism comprises a pair of tamping rings,
one of said tamping rings having a cross-sectional configuration similar to the cross-sectional configuration of the lower part of said space,
the other of said tamping rings having a flange extending downwardly into said space along its inner periphery for providing a ridge along the inside of the compacted material, and
means for sequentially tamping the material with said first tamping ring and then with said other tamping ring.
2. The molding apparatus set forth in claim 1 wherein said latter means actuates said first tamping ring a number of times before it sequentially actuates said other tamping ring a number of times.
3. The molding apparatus set forth in claim 1 wherein:
said mold box defines two openings extending into said mold box laterally of its longitudinal axis and along a common axis, and
a pair of core plugs reciprocally mounted on said apparatus, one for movement into and out of each of said openings.

13

4. The molding apparatus set forth in claim 1 wherein:

said latter means comprising a hydraulic cylinder connected to said mounting ring through a chain and sprocket drive first slowly and then more rapidly actuates said mounting ring through said space between said mold box and said core to overcome the adhesion of the compacted material to said

14

mold box and said core without damaging the compacted material.

5. The molding apparatus set forth in claim 3 in further combination with loading means for sequentially loading said space between the core and the mold box before each sequential actuation of said means for tamping the material.
